(57) **CLAIM**

We claim the ornamental design for a bottle, as shown.

DESCRIPTION

FIG. 1 is a perspective view of a bottle, according to the present invention;

FIG. 2 is a left side elevational view of the bottle of FIG. 1; FIG. 3 is a right side elevational view of the bottle of FIG. 1;

FIG. 4 is a front elevational view of the bottle of FIG. 1; FIG. 5 is a rear elevational view of the bottle of FIG. 1; FIG. 6 is a top plan view of the bottle of FIG. 1; and, FIG. 7 is a bottom plan view of the bottle of FIG. 1. The broken lines shown in the drawings are for illustrative purposes only and form no part of the claimed design.
